UNITED STATES PATENT OFFICE.

CLARENCE LIEDEL, OF MAYBEE, MICHIGAN.

VARIABLE INDUCTANCE.

Application filed March 24, 1923. Serial No. 627,414.

To all whom it may concern:

Be it known that I, CLARENCE LIEDEL, a citizen of the United States, residing at Maybee, in the county of Monroe and State 5 of Michigan, have invented new and useful Improvements in Variable Inductance, of which the following is a specification.

This invention relates to radio receiving apparatus, particularly that type employing 10 a crystal detector, and has for its object the provision of a novel compact apparatus including a peculiarly constructed and delicately variable inductance by means of which delicate adjustment may be made to 15 secure great sensitiveness and selectivity.

Another object is the provision of an apparatus of this character in which the core upon which the inductance is wound serves to enclose the detector and various binding 20 posts so that the entire device will occupy the minimum space and whereby the crystal detector will be protected against being accidentally touched and thrown out of adjustment.

25 An additional object is the provision of an apparatus of this character which will be very simple and inexpensive to manufacture, easy to control and operate, efficient in service, and a general improvement in 30 the art.

With the above and other objects and advantages in view, the invention consists in the details of construction to be hereinafter 35 more fully described and claimed and illustrated in the accompanying drawings in which—

Figure 1 is a side elevation of the device.
Figure 2 is a top plan view thereof.

40 Figure 3 is a cross sectional view on the line 3—3 of Figure 2.

Referring more particularly to the drawings, I have shown the body of my device as consisting of a cylindrical form or core 10 having a circular bottom 11. This core 45 may be formed of card-board, bakelite, formica, fiber, or any other insulating material. The upper edge of this core is preferably formed with an overhanging flange 12 which serves to retain in place and also 50 to protect a coil 13 of enameled wire of suitable gage wound spirally upon the core and having its outermost surface scraped free from insulation. The lower terminal 14 of this winding is connected with a binding post 15 which rises from the bottom 11 and which is designed for connection of the 55 aerial lead-in therewith. Also mounted upon the bottom in spaced relation to the binding post 15 is a second binding post 16 which is for one terminal of the phones 60 and which is connected with the binding post 14 with a wire 17. The upper terminal of the winding 13 is simply passed through a plurality of holes in the core or otherwise secured, as indicated at 18, whereby to be permanent or unconnected with any 65 of the mechanism.

Disposed upon the bottom 11 is an elongated metallic strip 19 which has one end pivoted by a binding post 20 which rises 70 from the base, and pivoted for rotatable movement upon the free end of this strip is a metal cup 20 which contains the crystal 21. This cup may be mounted upon the strip by means of a rivet 22 or other equivalent means.

The numeral 23 designates an angular metal strip which has one end offset downwardly to provide a bearing foot 24 pivoted on the base 11 by a binding post 25. The 80 free end of this angular strip carries an adjusting screw 26 upon which is mounted a "cat-whisker" 27 designed for engagement with the crystal. Intermediate its ends the strip 23 has threaded therethrough an adjusting screw 28 which has its free end bearing upon a metal plate 29 secured upon the bottom and formed at its edges with an upstanding lip or flange 30 which will prevent the free end of the screw 28 from slipping 85 off of the plate.

The binding post 25 is adapted for connection with the other terminal of the phones and the binding post 20 is adapted for connection with the ground wire. Connected with the binding post 20 is a section of flexible conducting cord or wire 31 which has its free end carrying a contact clip 32 which straddles the form with the free end of one arm 32 bearing against the 100 inside of the core and the free end of the other arm 34 formed with a lip 35 contacting with the coil 13. The connection of the wire 31 with the clip 32 might of course be made in different ways but it is really 105 preferable that the wire be connected with a post or stem 36 which is swivelly connected with the clip so as to prevent twisting and kinking of the wire or breaking when the clip is moved to different positions along the circumference of the coil.

110 The diagram of connection, or the "hook-

up" is shown in the detail views in which it will be observed that the aerial A is connected with the binding post 15, the ground wire G is connected with the binding post 20 and the terminals of the phones P are connected with the binding posts 16 and 25.

In the operation of the device tuning is effected by sliding the clip 32 transversely of the coil 13 for obtaining the rough adjustment and then by moving the clip circumferentially of the individual convolution engaged by it so as to make a delicate adjustment of the inductance in the circuit. Owing to the fact that the wire 13 is wound spirally upon the core it is apparent that by sliding the clip circumferentially of the core it may be progressed from one convolution to the next without utilizing its slidable function and owing to this peculiar arrangement it is obvious that a pin point adjustment may be made so as to obtain the greatest sensitiveness and selectivity. The current entering the binding post 14 from the aerial, divides, one portion passing through wire 14, coil 13, clip 32, wire 31, and binding post 20 to the ground, and the other portion passing through the phones P, binding post 25, strip 23, screw 26, "cat-whisker" 21, strip 19, and binding post 20, to the ground. In actual practice I have discovered that this circuit is very effective and sensitive and selective. Mechanically, adjustment to obtain a sensitive spot on the crystal is easily made owing to the pivotal mounting of the strip 19, the revolvability of the cup 20, and the adjustability of the "cat-whisker" holding screw 26, together with the adjustment of tension by means of the screw 28. It is to be seen that practically every conceivable adjustment of the detector is provided for so that the set will operate with the maximum efficiency and with the utmost ease. While I have shown and described the preferred embodiment of my invention, it is of course to be understood that I reserve the right to make such changes in the form,

construction and arrangement of parts as will not depart from the spirit of the invention or the scope of the subjoined claims.

What is claimed is:

1. In a radio receiving apparatus, an inductance consisting of a cylindrical core having enameled wire wound thereon spirally, the outermost surfaces of the successive convolutions being freed from insulation, and a slide contact consisting of a clip straddling the edge of the core and slidable transversely and circumferentially of said convolutions.

2. In a radio receiving apparatus, an inductance consisting of a cylindrical core having enameled wire wound thereon spirally, the outermost surfaces of the successive convolutions being free from insulation, and a slide contact consisting of a clip straddling the edge of the core and slidable transversely and circumferentially of said convolutions, a conducting wire, and a connecting stem connected with said wire and swivelly connected with said clip.

3. In a device of the character described, a cylindrical hollow core having a closed bottom for supporting auxiliary apparatus, said core being provided at its upper edge with an outwardly extending retaining flange, wire wound spirally upon the core and having its successive convolutions insulated one from another with the outer surfaces of the convolutions freed from insulation, a U-shaped clip engaged upon the wall of the core and slidable upon said flange, one arm of the clip having its free end formed with an inward extension of a V-shape having its vertex slidably engageable with said wire, the clip being movable transversely of all the convolutions or circumferentially thereof, and a take off connection swivelly connected with the bight portion of the clip, said flange being engageable by said extension for preventing removal of the clip from the core.

In testimony whereof I affix my signature.

CLARENCE LIEDEL.
